WEIGHING SCALE

Jean O. Reinecke, Chicago, Ill., assignor to Continental Scale Corporation, Chicago, Ill., a corporation of Delaware

Application October 30, 1956, Serial No. 43,598

Term of patent 14 years

(Cl. D52—10)

FIG. 1

Fig. 1 is a top view of a weighing scale embodying my new design;

Fig. 2 is a side view of the weighing scale; and

Fig. 3 is a front view of the weighing scale.

The dominant features of the weighing scale reside in the portions shown in full lines.

I claim:

The ornamental design for a weighing scale, as shown and described.
